COKING RETORT OVEN

Joseph Becker, Pittsburgh, Pa., assignor to
Koppers Company, Pittsburgh, Pa., a corpora-
tion of Delaware

Application August 5, 1937, Serial No. 157,493

6 Claims. (Cl. 202—143)

The present invention relates in general to coking retort ovens and comprehends more especially improvements in coking ovens having accessible passageways beneath a structural supporting mat in combination with cross regenerators that lie closely beneath the vertically flued heating walls for the coking chambers. The instant improvement is adapted for embodiment in coking retort ovens that are arranged to have their rich heating gas introduced into the heating flues either from refractory header-conduits that extend longitudinally of the coking chambers through the capitals of supporting pillar walls or according to the so-called underjet principle, and the improvement is further adapted for incorporation in coking ovens of the combination type as well.

The invention contemplates the provision of means to separately regulate for and thereafter flow into the upper part of each flame-flue, or of a pair of contiguous flame-flues, of vertically flued coking oven heating walls, with no significant diminution in pressure and by the shortest direct flow-path from individual regulators accessible beneath the oven-supporting mat, optional quantities of combustion air, or of heating gas, in addition to those introduced into the lower parts of said vertical heating flues, and by means of a separate distribution system therefor that is located in passageways positioned directly beneath regenerators for preheating underfiring media, said system being operable independently of those arrangements employed to introduce combustion media into the lower parts of the heating flues so that it can be utilized only at such times as it is advantageous to do so for establishing preferred thermal conditions in the heating flues and so that regulation of the heating media flowed from such a system can be established with readily accessible regulatory means and that the so regulated heating media will thereafter have an unimpeded and substantially direct flow-path into the heating flues, providing direct optionally regulable uniform or diversified heating vertically of the flame-flues severally and controllable uniformity or diversity of such conditions along the heating-walls horizontally.

The present invention thus also may be said to contemplate the provision of means whereby preferred diversified thermal zones can be established in the flue systems of coking ovens so that the coke plant operator may be furnished with a medium through which he is enabled to maintain diverse temperature levels at various levels

of the flue system for those occasions where the economic set-up is served by so doing.

The invention also contemplates the provision of an independently regulable system whereby the secondary combustion air or secondary fuel gas, that is introduced into the upper parts of all the vertical heating flues of a coke oven battery, will be of substantially uniform preheat throughout the heating-walls, the preheating step being recuperatively effected in the regenerator walls and by equal lengths of flow-paths therein, for the combustion media, to all of the heating flues and in such manner that the heat withdrawn from said regenerator walls for that purpose will give rise to no stresses, strains or shearing action in their brickwork or unsymmetrical thermal levels from ends to ends of the regenerator walls nor to dissimilar temperature conditions at similar levels thereof. In addition, the invention contemplates the provision of a system for the stated purpose which will obviate the formation therein of inaccessible accumulations of such suspended matter as may be carried by the combustion media and deposited therefrom in such system.

In the carbonization of coal for its by-products, the temperature to which the coal and the volatilized constituents are subjected bears importantly on the nature of the finished products and especially in the case of the distilled fluids their chemical structure and quantity is influenced to a great extent by the temperature they have encountered during processing. Higher temperatures tend to crack the volatilized fluids and promote the formation of compounds that are predominantly aromatic in nature, whereas lower temperatures promote the recovery of larger yields of liquid by-products having a relatively larger proportion of substances belonging to the aliphatic series of compounds. In consideration of these facts it becomes apparent that the temperatures maintained for example in the so-called "gas-collecting space," i. e. the crown-space between the top of the coking chamber and the top of the coal charge and through which the constituents volatilized from the coal mass pass in their path to the ascension pipe and collecting main and wherein a relatively large proportion of said constituents are subjected for a significant period to heat given off from the brick-work forming the top and sides of this space, become an important consideration and should therefore be capable of such regulable adjustment as will permit the oven-operator's establishing those heating conditions both along the

heating flues and especially in the region of the gas-collecting space, which are most suitable for the production of the particular by-products it is desired to manufacture. In other words, in 5 certain circumstances and situations, the economics of the coking process may be best served when a coking structure is adapted to provide in its flue system regulable zones of diversified heating therealong whereby the effects produced 10 in various sections of the coking chambers are subject to regulation so that, for example, hot bottoms and cooler tops or vice versa can be provided for the coking chambers, and among the objects of the present invention is the provision of 15 simple and novel means whereby diversified thermal conditions can be established at any one time in coke oven flues so that the pyrolytic reactions produced at different levels of the coking chambers can be controlled and altered at will. The 20 present invention is thus designed to contribute improved flexibility of operation and operating results to a structure embodying its principles.

By means of the present invention it is possible 25 to convert an existing design of coking retort oven, in which the manufacture of only high temperature coke was contemplated, into one readily adapted for the production of coke at medium temperatures, such cokes having a residuum of volatile matter therein which gives 30 them certain advantages when used in domestic heating equipment. Besides this, the subject of the invention makes it possible, in the same coking oven in which the medium temperature coke is produced, to convert, if preferred, the medium 35 temperature tars and gases, that normally contain higher percentages of aliphatic and paraffinic bodies than do bases and tars made at high temperatures, into typically high temperature tars that are predominantly aromatic in nature 40 and by raising the temperatures adjacent the gas-collecting space above that existing in those sections of the walls immediately adjacent the coal charge.

The device provided by the invention is also 45 of great utility for coke ovens in which, for any reason, it is found necessary to increase drastically the coking time from that for which the retort oven was especially designed, for it furnishes readily manipulated and directly effective 50 means whereby combustion of the reduced volumes of fuel burned during such intervals may be delayed somewhat, with the result that more equable distribution of these significantly smaller quantities of heat are obtained by its use during 55 such intervals.

The subject of invention is also adapted for embodiment in coking retort ovens of the combination type and will in no wise interfere with 60 normal operating procedure during such times as combination ovens are being underfired with fuel gases of low calorific value since it can be simply and readily excluded from any operating effect whenever desired. The invention has for further objects such other improvements and 65 such other operative advantages or results as may be found to obtain in the processes or apparatus hereinafter described or claimed.

According to the invention there is provided 70 in those walls that separate the flues of a coke oven heating wall, conduit means that branch laterally into the upper parts of a pair of heating flues positioned on opposite sides of the same flue-separating wall, and extend downwardly through those pillar walls, that structurally support the oven heating walls and also divide the

regenerative space beneath the coking chambers into gas-tight regenerators which course lengthwise of the coking chambers, and also extend through the oven-supporting mat and port beneath said mat in an accessible basement. The 5 conduits of the invention are preferably adapted to supply to each therewith connected heating flue from about one-tenth to one-fourth of the total air required to burn the maximum amount of fuel gas that is supplied to the lower ends of 10 said heating flues and they are furnished at their lower parts with valve means that are accessible from the battery basement, said valve means being preferably arranged to permit individual regulation of the air entering any one such conduit. 15 By means of these conduits it is thus possible, when desirable, to supply part of the combustion-air requirements to the heating flues from the battery basement, while the remainder may be passed through the regenerators, and, advantageously, by reason of the fact that valve means, for regulating the flow of air into the conduits provided by the invention, are readily accessible in the oven basement, said conduits may be rendered inoperative at any time and the total combustion-air introduced into the heating flues be withdrawn from the regenerators. Thus the coke oven operator can empirically determine those points at which the introduction of the combustion-air is best suited to existing circumstances to 30 produce optimum operating results.

By placing the conduits of the invention in the regenerator walls, the air passing through them is recuperatively heated by the absorption of heat from both the regenerator and heating-flue 35 walls, so that it is somewhat preheated before entering the heating flues. The so-introduced air also operates advantageously to promote uniformity of heat distribution in the different heating zones by operating as a diffusive medium for 40 transferring heat from adjacent localized areas that may be at temperatures higher than those surrounding them.

In the oven basement the conduits of the invention for an entire or partial heating wall may 45 be connected through their valve means with a common header-pipe into which the air is introduced before it is distributed to the individual conduits, or in those instances where such small amounts of air are carried to the heating flues 50 through said conduits that their valve means will permit only small amounts of air to flow therethrough when the associated flues are operating for down-flow, said conduits may be provided with individual ports into the basement. 55 If the former arrangement is preferred, the header-pipe may be furnished with valve means that are disposed for operation by that mechanism which reverses the flow of gases through the heating flues and regenerators.

According to the invention, this header-pipe 60 may also be connected with a source of preferably lean heating gas so that fuel gas in excess of that introduced into the bottom of the heating flues may be supplied directly to the flues at a point adjacent the gas-collecting space, where it can be burned with air coming from the lower parts of the heating flues to heat said space to a temperature above that obtaining in the flues' lower parts.

In the accompanying drawings forming a part 70 of the specification and showing for purposes of exemplification a preferred apparatus and method in which the invention may be embodied and practiced but without limiting the claimed in- 75

vention specifically to such illustrative instance or instances:

Figure 1 is a crosswise vertical section through a coke oven battery embodying features of the present improvement, said battery comprising coking ovens of the so-called underjet type, the section A—A of the view being taken longitudinally through a heating wall and along the line A—A of Figure 2, whereas the section B—B is taken through a coking chamber and a regenerator and along the line B—B of Figure 2;

Figure 2 is a composite vertical sectional elevation taken longitudinally of a coke oven battery in planes indicated by the lines C—C and 15 D—D of Figure 1;

Figure 3 is a horizontal section taken along the line III—III of Figure 2;

Figure 4 is a crosswise vertical section through a coke oven battery embodying features of the 20 present invention, said battery being of the type shown in Figure 1 but in which the rich fuel gas is introduced into the bottom of the heating flues by distributing ducts from a refractory header-conduit positioned in the brickwork of the pillar wall capitals, instead of according to the under-jet principle, the section E—E being taken along the line E—E of Figure 5, whereas the section 25 F—F is taken through a coking chamber and a regenerator and along the line F—F of Figure 5;

Figure 5 is a composite vertical sectional elevation taken longitudinally of a coke oven battery in planes indicated by the lines G—G, H—H and 30 K—K of Figure 4 and clearly shows how, in this embodiment, the duct means provided by the invention are not vertically disposed throughout their entire length from the battery basement to the upper part of the heating flues but instead are curved around the rich gas header-conduit in the pillar wall capitals;

Figure 6 is a horizontal section taken along the lines VI—VI of Figure 5; and

Figure 7 is an enlarged fragment of Figure 2 showing the relative arrangement of the distribution system for flowing rich gas to the heating flues from beneath the battery-mat and the distribution system of invention for supplying gasous media to the upper parts of the flues from beneath the battery.

50 The same characters of reference designate the same parts throughout the several views of the drawings.

Referring now to the drawings: the invention as shown in the several views of the drawings is embodied for purposes of exposition in a coke oven battery of the well-known Becker cross-over type and more particularly of his Patent No. 2,100,762 and is susceptible of being under-fired by either rich gas or preheated lean fuel gases, but it will be understood that the benefits provided by the present improvement are not necessarily restricted to coke ovens of the type shown in the illustrations since said benefits can be realized in any one of a large number of coke-oven types that are supported on piers in such manner as to provide accessible passageways therebeneath.

The coking retort oven battery shown in the drawings embodies in its construction a plurality of crosswise elongated heating walls 11 and a plurality of intermediate elongated vertical coking chambers 12. The heating walls 11 form the side walls of the respective coking chambers 12 and as shown in the drawings are supported by 70 the heavy supporting pillar walls 13 that ex-

tend crosswise of the battery and lengthwise of the coking chambers beneath their respective heating walls. The pillar walls 13 serve both to support the heating walls and to divide the regenerative space beneath the heating walls and 5 the coking chambers into a plurality of gas-tight individual regenerators that also extend entirely across the battery and in substantial parallelism with the heating walls. Each of the regenerators positioned between the pillar walls 10 13 is further sub-divided into a regenerator pair by the regenerator division wall 14 which serves to support the coal charge in the coking chamber 12 directly above it, and is in addition of such substantial and gas-tight construction that gases 15 may be maintained under relatively different pressures on the opposite sides of said division walls 14 so that the flow of different underfiring media through the checkerbrick contained in these different regenerator chambers 15 may be 20 maintained, without leakages from one chamber to the other taking place. Each regenerator of such a regenerator pair is furnished with an individual sole flue 16 that communicates by means of a plurality of ducts 17 with the checker- 25 bricks above, said ducts operating to promote a uniform distribution throughout the regenerator chamber of gases introduced into the ends of the sole flues.

The heating walls 11 of adjacent coking chambers are constituted of a plurality of individual vertically disposed heating flues 18 by means of partition walls that are transverse of the heating walls and are tied into the heating walls at their opposite sides and, at their lower ends, form 30 gas-tight connections with the masonry of the pillar walls. Alternate walls of these partition walls, that separate the flues of the heating walls, are higher than the intermediate ones. The higher of these partition walls 19 are flared at 35 their tops, as shown in the drawings, to provide a single passageway 20 for the pair of heating flues lying between two of such walls 19. The intermediate shorter partition walls 21 are stopped sufficiently short of the passageways 20 40 as not to impede the flow of gases through said passageway 20. The heating flues of each heating wall (with the exception of the end flues which are provided with individual control and cross-over ducts) are divided into groups of four 45 flues by the short walls 22 that divide the horizontal flue into a plurality of shorter horizontal flues 23. The flow of gases from or to the heating flues in each group passes through its horizontal flue 23 directly into the cross-over conduit 24, 50 that is above the middle partition 19 in each group, and into a corresponding group of flues in the heating wall on the opposite side of the oven. 55

The vertical heating flues 18 of the heating walls each communicate with two regenerators 60 15 that are located on opposite sides of the pillar walls 13 by means of ducts 42 through which the gases flowed from the regenerators pass into the lower parts of the heating flues. Beneath the regenerators is the battery-supporting mat 65 25 that is itself supported, by piers 26, above the ground level thereby providing passageways 27 in which access can be had to the mat from beneath as well as to such of the operating accessories as may be positioned there.

As shown in Figs. 1 and 2, rich underfiring gases that are not regeneratively preheated, are introduced into the flame-flues through rich-gas ducts 28 that rise vertically through the pillar walls and discharge into the heating flues at ports 70 75

29. At their lower ends said rich-gas ducts 28 communicate with a reservoir of rich gas outside the battery structure by means of a common distributor-header 30 for each heating wall, each such header 30 receiving rich gas from the reservoir therefor through the arterial rich-gas supply main 31 in quantities regulated by a gas-cock 32 that is adapted for operation by a reversing mechanism through the attached cable.
- 10 In the embodiment of the invention shown in Figs. 4 and 5 the rich underfiring gas is not introduced into the heating flues according to the underjet method but rather from header-conduits 33 that are made of refractory materials 15 and positioned in the brick work of the pillar-wall capitals. The gas delivered to each heating flue from a conduit 33, through an individual laterally disposed aperture therein, is regulated by a nozzle-brick 34 adapted for insertion in 20 said aperture.
- 20 As shown in Figs. 1 and 2 of the drawings, conduits 35 are incorporated in the pillar walls 13 that are directly beneath the heating walls of the ovens and are arranged to extend vertically 25 upwards from the battery basement entirely through said pillar walls and their capitals and also through the shorter heating flue partition-walls 21 to a point in their upper parts, whence they fork laterally by means of short ducts 36 30 into the heating flues on the opposite sides of a partition wall 21. Although the conduits of the invention may, if preferred, be placed in the flared flue partition-walls 19, it is preferred to extend them through the shorter walls 21 so 35 that the gases flowed through any flue-group of a heating wall can be kept segregated from those of all other flue-groups of that wall. The conduits 35 for the heating flues of two adjacent heating walls are connected individually by means 40 of pipe connections 37 and a flow-regulating orifice 38 with a common header-pipe 39 which is provided at both ends with valve means 40 that may be disposed for intermittent opening and closing by the mechanism employed to 45 reverse the flow of gases through the regenerative heating system and in such manner that said valve means are open, when the therewith communicating heating flues are operating as the flame or up-burning flues, and are closed when 50 these same flues are the down-flowing flues.
- 50 Sole channels 16 at both ends thereof are provided with flow boxes 41 for regulating the flow of underfiring media that enter the regenerators for preheating purposes before they are introduced into the heating flues through ducts 42 55 and for directing the combustion-products therefrom into the stack canal 43. When underfiring with regeneratively preheated fuel gases, such as blast furnace gas that is distributed along 60 the battery from gas-main 53, the regenerators and flow-boxes are so arranged, in respect of the regulating devices for and the sources of the waste-heat, the air and the fuel gas, that an air regenerator is always interposed between 65 the combustion-products regenerators and that regenerator used for preheating fuel gas, and in such manner that the regenerators for preheating inflowing fuel gas and combustion-air are adjacent to and on opposite sides of the same 70 pillar wall 13.
- 70 In the embodiment shown in Figs. 4, 5, and 6, the conduits 44 provided by the invention are shown in combination with an alternate means for flowing rich fuel gas into the heating flues, said means comprising a refractory bus or

header-conduit 33 located in the capitals of each pillar wall 13. Conduits 44 in this embodiment are not vertically disposed throughout their entire length but curve outwardly from the vertical median of the pillar-wall capitals and around the brick work of the conduits 33 before entering the flue partition-walls 21, as clearly shown in Figs. 5 and 6 of the drawings.

Both forms of the conduits of invention 35, and 44, can be utilized to carry air or heating 10 gas into the upper parts of the heating flues. For the purpose of introducing heating gas at such points in the flues, the distributor-headers 39 are communicably connected with the blast furnace gas supply-main 46 and regulated 15 amounts of that gas are introduced into headers 39 through gas-cocks 45, which may be disposed for actuation by the gas-flow reversing-mechanism through cable 47: during such periods of operation it is obvious that valve means 40 must 20 be tightly closed at all times so that there will be no transfer of gases between the atmosphere of the passageways beneath the ovens and said distributor-header 39.

The air distributed to the heating flues by 25 the conduits 35 and 44 is ordinarily withdrawn from the space beneath the battery supporting- 30 mat by the natural draft of the stack means, but it can be also introduced into the distributor-headers from an outside source as well as under 35 pressures in excess of atmospheric when operating circumstances and results make it advisable. Usually, however, it is preferred to employ the natural draft of a stack means and the total 40 amount of air entering the heating flues, under 45 its influence, is apportioned between that entering from sole flues 16 and from headers 39 by 50 graduating the apertures 48 of the flow boxes 41 with draft-bars 49 in the manner well-known in the practice. The heating media entering the 55 individual conduits 35 and 44 from said headers 39 are subject to regulation by means of orifices 38 which are individual to each of the conduits of the invention and may be varied in size as required to produce the desired heating effects 40 in the heating flues associated therewith.

A coking retort oven provided with the present improvement receives an improved flexibility in 55 operation and is susceptible of having established in its heating flues, heating zones having a diversity of temperature levels and heating effects, which advantageously assist the oven-operator to increase the range of results he can produce or the field of materials that can be manufactured in the ovens. In order to point out more 60 clearly the potentialities of an oven provided with the present invention, the following brief description of operative possibilities is given. From a quantity of fuel gas introduced into the bottoms of the heating flues a variety of heating 65 effects and products of carbonization can be produced. For example, let it be assumed that the ovens shown in the drawings are operating at the normal coking rate for which they were especially designed, and further assume that the 70 walls are being heated by means of a fuel gas that does not require regenerative preheating and is flowed into the heating flues at their lower parts, where said gas is admixed with sufficient air, that is likewise introduced into the lower 75 parts of said heating flues but from the sole flues and the regenerators through ducts 42 and in quantities regulated by changeable plugs 51 that are positioned concentrically of the regenerator ports and which cause the air to enter the flues 75

in the form of an annular ring and rise vertically thereinto with little tendency to be distorted from a stream-line flow-path, said air being introduced, into the flues, in quantities just sufficient to effect perfect combustion of the quantities of fuel gas employed. The air and gas will mix and burn as they flow along the flues: the thereby evolved heat is absorbed by the heating walls of the coking chambers and a certain thermal equilibrium is established between the heating walls and the burning gases. Coke and by-products will be produced having definite characteristics and analyses. Now assume that in consequence of demand it is desirable to produce coke that has a somewhat higher residue of volatile constituents, such as will be formed by decreasing the temperature of the heating walls, and at the same time it becomes important that the pyrolytic decomposition of the distillates, passing through gas-collecting or crown space 52, be made more extensive for the purpose of altering the characteristics of all or some of the by-products. Both these desired operating results can be promoted without altering the existing flow of combustion media to the flues by introducing into said flues at some point nearer the crown-space, an empirically determined portion of that quantity of air which was formerly introduced into the flues entirely at the bottoms thereof. To this end, the conduits of the invention, which had not been previously in operation, are now put into service by decreasing the effective cross-sectional area of the air-ports 48 of the flow-boxes, and by opening the previously closed valves 35 of the distributor-headers 39 whereby air is drawn directly from the passageways beneath the battery supporting-mat and flowed into the upper parts of the individual heating flues in a direct flow-path and with no significant loss in velocity-head after being both regulated and introduced by orifices 38, into each of the conduits 35 of Fig. 1 or into the conduits 44 of Fig. 4 individually, and under stack-draft. In the upper parts of the heating flues, this air mixes with and burns any unburned heating gas. The heat thereby evolved is applied adjacent to the brickwork of the oven crown 52 to increase the temperature of the region through which volatilized products from the coal must pass, thus providing for their more extensive decomposition; at the same time, less of the heat content of the volume of fuel gas being used, is applied to those sections of the flues adjacent the coal charge, thereby increasing the percentage of volatile matter in the coke residue of the distillation process.

In other circumstances it may be desirable, for a certain purpose, to operate with wall temperatures reduced from those previously obtaining, but with cooler tops rather than with the hotter tops as described in the above-mentioned coking conditions. The establishing of these new coking conditions can be promoted, for example, by reducing the amount of fuel gas introduced into the bottom of the heating flues and at this point also introducing only sufficient air to provide for complete combustion of said reduced volumes of fuel gas while at the same time flowing quantities of excess air into the tops of the flues through the conduits of the invention: the thermal units required to heat this excess air will tend to cool the oven tops and its heat content can of course be thereafter recovered in the regenerators for reuse in the re-

verse flow-period of the regenerative heating cycle.

The invention can also be used to promote uniformity of heat distribution along oven flues more especially in those instances where the coking time is sharply increased from that for which the ovens were designed and for which an existing oven-setting had been made. At such increased coking times, the velocity of the gases through the flues is significantly reduced which promotes the liberation of the coking heat of the gases in a shorter section of the flues: however, by introducing only a part of the air required for the combustion of the reduced volume of fuel gases into the lower parts of the heating flues and the remainder into their upper parts, through the conduits of the invention, there will result a tendency toward a significant and desirable elongation of the flames at longer coking times.

The subject of invention can also be used for the addition of more thermal units to the heating flues than are introduced into the lower ends thereof, a possibility which, for example, may be exploited during those periods when the coking time is relatively shorter than normal, and when it is desired to increase still further the temperatures at the oven tops in order to produce further decomposition of the larger volumes of distillates flowing through the oven crown. At such times, heating gases of any preferred type can be introduced by means of the conduits 39, 44 into the tops of the flues where they can be burned by such air as is introduced into the bottom of the heating flues and is in excess of that which is required to burn the rich gas also introduced into the flues at that point.

All these methods of operation are accomplished by short directly effective and readily regulable means severally accessible at the distributed points where such flame-flue regulation is needed.

The invention as hereinabove set forth is embodied in particular form and manner but may be variously embodied within the scope of the claims hereinafter made.

I claim:

1. In a battery of cross-regenerative coking retort ovens with vertically flued heating walls having partition walls between the heating flues and regenerators separated by division walls for joint inflow of primary air or separate inflow of primary fuel gas and primary air simultaneously to the heating flues at their lower parts; and alternative primary fuel gas supply means with vertical ducts in the regenerator division walls for alternatively supplying unregenerated primary fuel gas to the lower part of the heating flues for combustion with primary air from a regenerator for simultaneous inflow of primary air; and auxiliary supply means with vertical ducts extending through the regenerator division walls and the heating flue partition walls between the vertical heating flues into communication with the so partitioned heating flues at their upper parts but well below their tops for supplying secondary combustion media thereto for combustion with residual primary combustion media from the lower parts of the heating flues; the combination of secondary air supply means and secondary fuel gas supply means for supplying secondary air and fuel gas to the auxiliary supply means, said secondary air and said secondary fuel gas supply means being optionally operable alternatively relative to each other and being separate from and operable independently.

of the primary air and gas regenerators and primary fuel gas supply means, for separate selective operation for flow of either secondary air or fuel gas to the upper parts of the heating flues 5 during flow of primary air or air and gas thereto by the primary supply means therefor.

2. In a battery of cross-regenerative coking retort ovens with vertically flued heating walls having partition walls between the heating flues 10 and regenerators separated by division walls for inflow of primary air to the heating flues at their lower parts; and primary fuel gas supply means with vertical ducts in the regenerator division walls for supplying an unregenerated 15 primary fuel gas to the lower part of the heating flues for combustion with primary air from regenerators for inflow of primary air; and auxiliary supply means with vertical ducts extending through the regenerator division walls and the 20 heating flue partition walls between the vertical flues into communication with the so partitioned heating flues at their upper parts but well below their tops for supplying secondary combustion media thereto for combustion with residual primary 25 combustion media from the lower parts of the heating flues; the combination of secondary air supply means and secondary fuel gas supply means for supplying secondary air or fuel gas to the auxiliary supply means, said secondary 30 air and fuel gas supply means being separate from and operable independently of the primary fuel gas supply means and the primary regenerators, for separate operation for flow of secondary air or fuel gas to the upper parts of the 35 heating flues during flow of primary air and fuel gas thereto by the primary supply means therefor.

3. In a battery of cross-regenerative coking retort ovens with vertically flued heating walls having partition walls between the heating flues 40 and regenerators separated by division walls for joint inflow of primary air or separate inflow of primary fuel gas and primary air simultaneously to the heating flues at their lower parts; a structural pad supporting said regenerator and itself supported above a sub-structure providing accessible passageways throughout the basement of the battery; and alternative primary fuel gas supply means comprising a lower horizontal distributor conduit with upper vertical ducts in the regenerator division walls for alternatively supplying unregenerated primary fuel gas to the lower part of the heating flues for combustion with primary air from a regenerator for simultaneous inflow of primary air; and auxiliary 45 supply means in the basement passageways with vertical ducts extending from the same through the supporting mat, the regenerator division walls, and the heating flue partition walls between the vertical heating flues into communication with the so partitioned heating flues at their upper parts but well below their tops for supplying secondary combustion media thereto for combustion with residual primary combustion media from the lower parts of the heating flues; the combination of secondary air supply means and secondary fuel gas supply means in the accessible basement passageways for supplying secondary air and fuel gas to the auxiliary supply 55 means, said secondary air and secondary fuel gas supply means being optionally operable al-

ternatively with each other and being separate from and operable independently of the primary air and gas regenerators and primary fuel gas supply means, for separate selective operation for flow of either secondary air or fuel gas to the upper parts of the heating flues during flow of primary air or air and gas thereto by the primary supply means therefor.

4. In a battery of cross-regenerative coking retort ovens with vertically flued heating walls 10 having partition walls between the heating flues and regenerators separated by division walls for inflow of primary air to the heating flues at their lower parts, primary fuel gas supply means comprising a lower horizontal distributor conduit 15 with upper vertical ducts in the regenerator division walls for supplying an unregenerated primary fuel gas to the lower part of the heating flues for combustion with primary air from regenerators for inflow of primary air, and auxiliary supply means for supplying secondary combustion media to the heating flues; and in which said auxiliary means is constituted of a header conduit in an accessible passageway beneath the battery, and regulable vertical ducts 20 extending from the header directly upwardly from the same through the regenerator division walls and the heating flue partition walls until into communication with the so-partitioned heating flues at their upper parts but well below 25 their tops for combustion with residual primary media from the lower parts of the flues, with substantially equal flow paths and without substantial loss in velocity head between the places of regulation and the communication of the vertical ducts with the heating flues, and secondary air supply means for the header, said secondary air supply means, its header and the vertical ducts therefrom being separate from and operable independently of the primary air regenerators and primary fuel gas supply means, for 30 separate selective operation for flow of secondary air to the upper parts of the heating flues during flow of primary air and fuel gas by the primary supply means.

5. Apparatus as claimed in claim 3 and in which the lower horizontal distributor conduit for the primary fuel gas supply means is also disposed horizontally within the capital of the regenerator wall within which its vertical duct means and the vertical ducts for the auxiliary supply means are both also disposed vertically, and in which the vertical ducts for the auxiliary supply means are curved around the horizontally disposed horizontal distributor conduit of the primary fuel gas supply means in the same regenerator division wall therewith.

6. Apparatus as claimed in claim 4 and in which the lower horizontal distributor conduit for the primary fuel gas supply means is also disposed horizontally within the capital of the regenerator wall within which its vertical duct means and the vertical ducts for the auxiliary supply means are both also disposed vertically, and in which the vertical ducts for the auxiliary supply means are curved around the horizontally disposed horizontal distributor conduit of the primary fuel gas supply means in the same regenerator division wall therewith.
